CONTROL SYSTEM

David E. Shoultz and Harold W. Lord, Schenectady, N. Y., assignors to General Electric Company, a corporation of New York

Application February 27, 1936, Serial No. 66,930
Renewed July 29, 1938

19 Claims. (CL 271—2.6)

This invention relates to control systems, more particularly to register control systems for apparatus having an element operating on a strip of material, and it has for an object the provision of a simple, accurate, reliable and improved system of this character.

One example of an application of apparatus of this character is found in multi-color continuous web printing. In this type of printing, it is sometimes necessary to dry the ink of one color before the next impression of a different colored ink is made. This requires considerable spacing between the printing units and very often some artificial method of drying. Owing to atmospheric changes and other variable factors, the length of web between successive printing units will stretch or shrink slightly, so that the color imprinted by the second printing unit is not in register with the first color, although the apparatus was originally set up to print the two colors in register with each other. Generally this variation is not cumulative, but it will tend to vary within certain limits.

For most multi-color work, it is necessary to register the colors within plus or minus .01 inch, which is approximately the width of a very fine pencil line. It is, thus, necessary to detect and correct inaccuracies of register of this amount or less. In order to accomplish this, it is necessary to obtain this same accuracy in timing the operation of the second printing cylinder that is obtained timing the passage of a reference mark or point on the strip.

In carrying the invention into effect in one form thereof, a light sensitive device is provided for producing an electrical impulse in response to the passage of a mark on the strip, and a second light sensitive device is provided for producing an electrical impulse in accordance with the position of the element which operates on the strip. Means controlled by these impulses are provided for correcting the relationship between the element and strip when the time interval between impulses exceeds a predetermined amount. As long as the time interval between these impulses remains less than this predetermined amount, no correcting action is initiated. An additional aspect of the invention is the provision of means for indicating the positional relationship between matter or designs printed on the strip and the element which operates thereon. Indications are produced to indicate the conditions of positional disagreement in which the operating element is "ahead" of a point on the strip, 55 positional disagreement in which the element is

"behind" a point on the strip, and positional agreement or correct register.

In illustrating the invention in one form thereof, it is shown as applied to multi-color continuous web printing apparatus for controlling the register of successive color printings. It will be understood however, that the invention also has application to other industrial apparatus having an element operating on a strip of material.

For a better and more complete understanding of the invention, reference should now be had to the following specification and to the accompanying drawings, of which Fig. 1 is a simple diagrammatic view in perspective of multi-color continuous rotary web printing apparatus, and Fig. 15 2 is a simple diagrammatical representation of an embodiment of the invention in a control system for maintaining exact register between the successive colored ink impressions imprinted on a continuous traveling web by the apparatus of 20 Fig. 1. Referring now to the drawings, a strip of material 10 is passed between rolls 11, 12 constituting a printing press unit. These rolls print a colored ink design on the strip which is repeated in succession, once for each revolution of the 25 rolls. Simultaneously therewith a succession of reference marks or indicia 13 are printed in a track near the edge of the strip and in predetermined relationship longitudinally of the strip with respect to the designs. It is not necessary that 30 these reference indicia should have any particular relationship with respect to the designs. It is only necessary that the relationship between the reference marks and their associated designs shall be uniform.

In order that the colored ink design shall have sufficient opportunity to dry before the next color is applied, considerable spacing is provided between the printing cylinders 11, 12 and the printing cylinders 14, 15 which constitute the next 40 printing unit. As shown in Fig. 1, this spacing is produced by causing the web 10 to pass underneath the guide roll 16 and then upwardly over guide rolls 17 and 18 and again downwardly and underneath guide roll 19 before entering the 45 printing cylinders 14, 15 of the second unit. A different colored ink is impressed on the strip by the printing cylinders 14, 15, and it is necessary that this second printing of a different colored ink shall take place in very accurate register with 50 the design impressed on the strip by the printing cylinders 11, 12. To this end a succession of reference marks or indicia 20 are impressed on the strip by the printing cylinders 14, 15 in predetermined longitudinal relationship with respect 55

to the colored ink designs impressed on the strip by the cylinders 14, 15. These reference indicia 20 are illustrated as printed in a track along the distant edge of the strip.

5 The printing units 11, 12 and 14, 15 are driven by any suitable driving means such for example as represented by the electric motor 21 to the drive shaft of which the cylinders are connected through suitable driving connections as illustrated. It will be observed that a differential driving device 22 is included in the driving connections between the electric motor 21 and the cylinders 14, 15. The input element 22a of this differential device is provided with worm wheel gear teeth which mesh with a worm member 23, which in turn is driven by a small electric motor 24. When the motor 24 is at rest, the friction of the worm gearing prevents the input element 22a from turning so that the electric driving motor 21 drives the printing cylinders 14, 15 as through a direct driving connection. However, when the electric motor 24 rotates the input element 22a in one direction or the other, the position of the printing cylinders 14, 15 with respect to the printing cylinders 11, 12 is retarded or advanced depending upon the direction of rotation.

In order to detect any inaccuracy in the register of the colors imprinted by the first and second printing units, suitable light-sensitive means are provided for producing electrical impulses in response to the passage of the reference indicia 13 and 20, and these impulses are utilized to control the electric motor 24 to correct the positional relationship of the printing cylinders 14, 15 with respect to the designs previously impressed on the strip by the printing cylinders 11, 12.

This light sensitive apparatus is illustrated as a scanning unit for responding to the reference indicia 13 and a second scanning unit for responding to the reference indicia 20. The first scanning unit is illustrated as comprising a lamp 25 for illuminating the path of the indicia 13 and a photoelectric cell 26 for responding to the passage of the marks 13 for producing controlling electric impulses. Similarly, the second scanning unit comprises a lamp 27 for illuminating the path of the reference indicia 20 and a photoelectric cell 28 for responding to the passage of these indicia 20 for producing controlling electrical impulses. These scanning units are so positioned longitudinally with respect to the designs that when the colored ink designs impressed on the strip by the printing cylinders 11, 12 and printing cylinders 14, 15 are in correct register, the impulses produced by photoelectric cells 26 and 28 occur substantially simultaneously.

Although the correcting motor 24 may be of any suitable type, it is illustrated as a direct current motor provided with split series field windings 29 and 30. Energization of the motor 24 through one of the field windings causes the motor to rotate in one direction and to produce a corresponding correction in the position of the printing cylinders 14, 15 relative to the designs previously printed on the strip, and energization of the motor through the other field winding causes the motor to operate in the opposite direction and likewise to produce a correction in the opposite direction.

As shown in Fig. 2, rectified alternating current is supplied by means of a suitable electric valve 31 through the field winding 29 and armature of motor 24 for rotation of the motor in one direction and similarly rectified alternating cur-

rent is supplied by means of a similar valve 32 through the field winding 30 and armature of the motor 24 for rotation in the opposite direction. Although the electric valves 31 and 32 may be of any suitable type, they are preferably of the three-electrode type into the envelope of which a small quantity of an inert gas is introduced after exhaust. The presence of this gas within the tube serves to convert the usual pure electronic discharge into an arc stream thereby constituting the tube an electrostatically or grid controlled arc rectifier. The anodes 31a and 32a of the valves 31, 32 are respectively connected to the terminals of the split field windings 29 and 30 and through these windings to one terminal of the armature of the motor 24 whilst the cathodes 31b and 32b are connected through a secondary winding of a supply transformer 33 and an adjustable resistance 34 to the opposite terminal of the armature of motor 24. The primary winding of the transformer 33 is connected to a suitable source of alternating voltage represented by the two supply lines 35. Preferably, the valves 31, 32 are of the hot cathode type and are therefore illustrated as provided with heating elements 25 which are supplied with electrical energy through an intermediate portion of the secondary winding of the supply transformer to which they are connected as illustrated.

Electric valves 31, 32 when supplied with alternating voltage conduct current only during that half cycle of the alternating voltage in which the anode voltage is positive with respect to the cathode voltage. The discharge is initiated in either of the valves when the voltage of either grid 31c, 32c respectively becomes more positive than a predetermined critical value. Once the discharge has started, the grid is powerless to control the flow of current during the remainder of that half cycle and the current flowing in the anode circuit can only be interrupted by physically interrupting the circuit or by reducing the voltage of the anode to zero with respect to the voltage of the cathode. Thus the current flow is interrupted when the anode voltage passes through zero value at the end of a positive half cycle of applied voltage.

A pair of similar electric valves 36 and 37 are provided for controlling the energization of the valves 31 and 32 respectively. The valves 36 and 37, though similar to the valves 31 and 32, are supplied from a source of direct voltage represented by supply lines 38 and 39. As indicated in the drawings, the upper supply line 38 is positive and the lower grounded supply line 39 is negative. Direct voltage for energizing the line 38, 39 may be obtained from any suitable source, such for example as the electric valve rectifying apparatus 40 within the dotted enclosure. This rectifying apparatus is in turn supplied from a suitable source of alternating voltage such as the source 35 to which it is connected through the supply transformer 41. Inasmuch as this rectifying apparatus per se is standard apparatus sold on the market and does not constitute any part of this invention a detailed description of its structure and operation is omitted. It is sufficient to understand that it rectifies the alternating voltage supplied from the source 35 and supplies a direct voltage to the lines 38 and 39.

The anodes 36a and 37a of the valves 36 and 37 are connected together by means of two resistances 42 and 43 which as shown are connected in parallel with each other to form a bridge. An 75

Intermediate point of the resistance section 42 is connected to the upper positive supply line 38, whilst an intermediate point of the lower resistance section 43 is connected through a portion 5 33a of the secondary winding of the transformer 33 to the cathodes of the valves 31, 32. The voltage induced in portion 33a of the secondary winding is of such magnitude and phase angle that the valves 31, 32 are held at cut off when 10 valves 36, 37 are non-conducting. The grids 31, 32c of valves 31, 32 are respectively connected to opposite bridge points 44, 45 as illustrated.

A pair of voltage dividers are connected across the direct voltage supply lines 38, 39. The first 15 of these voltage dividers comprises a plurality of resistance sections 46, 47 and 48 and the second of these dividers comprises resistance sections 49 and 50.

Preferably, the valves 36, 37 are of the hot cathode type and are illustrated as provided with filamentary cathodes 36b, 37b, which are connected in parallel with a portion of the secondary winding of the supply transformer 41 through which energy is received for heating the filaments to 25 the required degree of incandescence. The midpoint of this portion of the secondary winding is connected through conductor 51 to the conductor 52 which constitutes the junction point between the resistance sections 49 and 50 of one 30 of the voltage dividers. It will thus be seen that the cathodes 36b, 37b are normally at a voltage that is negative with respect to the voltage of the anodes 36a, 37a.

Impulses from the scanning head 25, 26 are 35 amplified by means of a two-stage amplifier 53 and conducted to the grid 37c of the valve 37 and similarly impulses from the scanning head 27, 28 are amplified by means of two-stage amplifier 54 and conducted to the grid 36c of electric 40 valve 36. These two-stage amplifiers are standard devices, well understood by persons skilled in the art and obtainable on the market. They do not in themselves constitute a part of the invention. For this reason a detailed description of 45 their structure and operation is omitted. It is sufficient to understand that the photoelectric cells 26, 28 are respectively connected to the grids of the valves 55, 56 constituting the first stage of each amplifier respectively and that the anodes 50 of the valves 57, 58 constituting the second stages of these amplifiers are respectively connected to the grids 36c, 37c of the valves 36, 37. The cathodes of all of the valves 55, 56, 57 and 58 are connected to the negative supply line 39 whilst 55 the anodes of the first stage valves 55 and 56 are connected through conductor 59 to the point 47a on the voltage divider and the anodes of the second stage tubes 57, 58 are respectively connected through resistances 60 and 61 to the point 46. 60 of the voltage divider, the voltage of which point is more positive than the voltage of the point 47a. The voltages applied to the grids of the second stage tubes 57 and 58 are of such a value that both valves are normally conducting, with the 65 result that the points of the resistances 60, 61 to which the grids of the valves 36, 37 are connected are sufficiently negative to hold the valves 36, 37 at cut-off.

As in the case of the valves 31, 32, once the 70 valves 36, 37 become conducting, it is no longer possible to control or interrupt the current flow of these valves by the grid voltage. Since the valves 36, 37 are energized from a direct current source, once the current flow is initiated, it will 75 continue indefinitely, unless some special means

are provided for physically interrupting the anode circuit or for reducing the voltage of the anode to zero with respect to the cathode voltage. For the purpose of commutating the valves 36, 37 additional electric valve apparatus comprising 5 a half-wave rectifying valve 62 and a full wave rectifying valve 63 are provided.

With the foregoing understanding of the elements and their organization in the completed system, the operation of the system itself will 10 readily be understood from the following detailed description:

Assuming the condition of correct register, i. e., the printing cylinders 14, 15 producing an impression on the strip 10 in correct register with 15 the design previously printed thereon by the first printing unit 11, 12, a reference mark 13 will pass beneath the scanning head 25, 26 simultaneously with the passage of a reference mark 20 beneath the scanning head 27, 28. As a result, simultaneous electrical impulses are produced in the circuit of both photoelectric cells 26, 28. These electrical impulses are applied to the grids of the first stage tubes 55, 56 and produce a momentary increase in current flowing through these tubes. 25 This increase in current produces a voltage drop across the resistances 60 and 61 thereby decreasing the magnitude of the positive voltage applied to the grids of the valves 57, 58. In consequence of this decreasing grid voltage, the current flowing through the valves 57, 58 is decreased with the result that the voltage drop across the resistances 60, and 61 is also decreased and the voltage of the grids 37c and 36c which are respectively connected to the negative terminals of 30 these resistances become sufficiently positive to render the valves 36 and 37 conducting.

The path of the current through the valve 37 is traced from the positive supply line 38 through the left-hand portion of the resistance 42 through valve 37, conductors 51 and 52 and resistance 50 to the negative side of the supply line. Similarly, the path of the current flowing through the valve 36 is traced from the supply line 38 to the right hand portion of the resistance section 42, through the valve 36 and thence through conductors 51, 52 and resistance 50 to the negative side of the supply source. These currents through the valves 36 and 37 produce a voltage drop through both halves of the resistance 42 thus maintaining the bridge points 44 and 45 at the same relative voltage with respect to each other and with respect to the point of connection of the cathodes to resistance 43. Thus, the voltage relationship between cathodes and grids of valves 31, 32 remains unchanged and these valves remain non-conducting. Consequently the motor 24 remains unenergized and no correcting action is initiated.

The current flow through the valves 36 and 37 and through the resistance 50 increases the voltage drop across the resistance 50 so that the upper terminal thereof becomes increasingly positive. A capacitance 66 and a resistance 66a connected in series therewith are connected in parallel with the resistance 50 and one terminal of this capacitance is connected through a portion of the secondary winding of the supply transformer 67 to the grid of the electric valve 62. Consequently, as the upper terminal of the resistance 50 becomes 70 increasingly positive the capacitance 66 which is connected through conductor 68 to the upper terminal of the resistance 50 begins to charge. The plate of the capacitance that is connected to the grid becomes charged with a positive voltage and 75

after a predetermined interval of time, the grid of the valve 32 becomes sufficiently positive to render the valve conducting. As a result current flows in the output circuit of the valve through the primary winding of a transformer 33 which induces a voltage in the secondary winding. When this voltage reaches a sufficient magnitude, the valve 33 breaks down and becomes conducting and current flows from the anode 33a to the cathode and then through conductor 38 and resistance 50 to the negative side of the supply line.

This current momentarily raises the potential of the upper terminal of the resistance 50 to a very high positive voltage thereby rendering the cathodes 36b and 37b positive with respect to the anodes which is the same in effect as rendering the voltage of the anodes negative with respect to the cathodes. The result of this is to render the valves 36, 37 non-conducting. By this time, the charge on the upper plate of the condenser 36 has risen to such a high positive value that it produces a discharge from the anode 33b of the tube 33 to the cathode, thereby allowing the charge to leak off the conductor and leave the system in a reset condition.

If now the length of the strip between the first and second printing units should increase for same cause or other, the cylinders 14, 15 of the second unit would print "late" with respect to the design printed on the strip by the first printing unit and thus the color impressed by the second unit would be out of register with the design printed by the first unit. Likewise, the index marking 20 would be late with respect to the corresponding index marking 13 so that an electrical impulse would be produced in the circuit of photoelectric cell 26 before the corresponding impulse would be produced in the circuit of the photoelectric cell 28.

This impulse energizes the electric valve, 37, in the manner set forth in the foregoing description, thereby causing the valve 37 to become conducting. The current flow through this valve and the resistance 50 produces a voltage drop across the resistance 50 so that the voltage of the cathode of both valves become increasingly positive. However, the voltage does not become sufficiently positive to interrupt the current flow of the valve 37 but it does become sufficiently positive to prevent energization of the valve 36 by a subsequent impulse transmitted to its grid from the photoelectric cell 28. Consequently, the valve 37 is rendered conducting and the valve 36 is maintained at cut off.

The current flow through the valve 37 lowers the voltage of the left-hand terminal 45 of the resistance 42 thereby rendering the voltage of the grid 32c of the valve 32 increasingly negative. On the other hand, the voltage of the point 44 at the right-hand terminal of the resistance 42 remains at the same high positive value as the upper line 38 of the supply source because no current is flowing through the valve 36. Since the cathodes 31b and 32b of both valves are connected to the middle point of the resistance section 43, the voltage of both cathodes is decreased by half the amount of the difference in voltage between the points 44 and 45. This has the same effect as raising the voltage of the grids of these valves. However, since the voltage of the grid 32c has already been decreased owing to the voltage drop across the left hand section of the resistance 42, the valve 32 is held at cut off and does not become conducting. The valve 31, on the other hand, since its grid voltage has not been

decreased, becomes conducting and passes current from the anode to the cathode through conductor 70, secondary winding of transformer 33, conductor 71, resistance 34, armature of motor 24, field winding 28 and conductor 72 to the anode.

As a result of its energization, the motor 24 rotates the input member 22a of the differential 22 in such a direction as to advance the position of the printing cylinders 14 and 15 relative to the design previously printed thereon by the printing cylinders 11, 12. After a predetermined interval of time determined by the constants of the circuit, the valve 37 is rendered non-conducting in the manner previously set forth in the foregoing description. As a result of the deenergization of the valve 37, the valve 31 likewise is deenergized and ceases supplying current to the motor 24. The motor 24 then ceases rotating after having advanced the position of the cylinders 14 and 15 a predetermined amount.

If the inaccuracy in register has not been fully corrected, the foregoing operation will be repeated when the next reference mark 13 passes beneath the scanning head 25, 26.

When the inaccuracy in register becomes less than a predetermined negligible amount, the time interval between the impulses produced in the circuits of the photoelectric cells 26 and 28 will become less than a predetermined value so that for practical purposes, these impulses may be considered as taking place simultaneously. However, the electric valve apparatus is extremely sensitive and would therefore respond to produce a correction even when the interval between impulses is so infinitesimal as to be of negligible importance. Therefore in order to render the system less sensitive and to eliminate continuous hunting action of the apparatus in seeking to correct negligible inaccuracies, it is necessary to increase the interval of time between impulses within which both electric valves 36 and 37 will be energized by the impulses and no correcting action initiated as explained in the foregoing. To this end, a plurality of condensers 13, 14, 15 of different capacities are connected so that a desired amount of capacity may be connected in parallel with the resistance 50 by means of a selector switch 76. The effect of connecting the capacity in parallel with the resistance 50 is to increase the time constant of the circuit of electric valves 36 and 37 and thereby to increase the time interval between impulses in the circuits of the photoelectric cells 26, 28 within which both valves 36 and 37 will be energized in response to the impulses.

If the length of strip between the first and second printing units shrinks, the second printing units 14, 15 will print "early" with respect to the design already printed by printing unit 11, 12. In consequence, an impulse will be produced in the circuit of photoelectric cell 28 before the impulse is produced in the circuit of photoelectric cell 26. This will cause the valves 36 and 37 to become energized in a manner identical with that already described for the energization of valves 37 and 31. The valve 32 will pass current to the motor 24 through the other field winding 30, thereby causing the motor 24 to rotate in the opposite direction so as to retard the position of the printing cylinders 14 and 15 with respect to the design printed by the cylinders 11, 12.

After a predetermined interval of time, the valves 36 and 32 are rendered non-conducting in the previously described manner and the motor 24 comes to rest after having corrected the

position of the cylinders 14 and 15 a predetermined amount. If the inaccuracy is not fully corrected this action will be repeated until the impulses produced by reference indicia 18 and 20 take place within the predetermined time interval in which both valves 38 and 37 become energized and no further correcting action is initiated. It will thus be apparent that motor 24 provides a visual indication of the positional relationship of the printing cylinder elements 14, 15 and the printed matter on the strip 10, i. e., rotation of the motor 24 in one direction indicates positional disagreement in one direction, rotation of the motor in the opposite direction indicates positional disagreement in the opposite direction, and the motor at rest indicates correct register.

Although in accordance with the provisions of the patent statutes, this invention is described as embodied in concrete form and operating in a specific manner, it will be understood that the elements, apparatus and connections shown and described are merely illustrative and that the invention is not limited thereto since alterations and modifications will readily suggest themselves to persons skilled in the art without departing from the true spirit of this invention or from the scope of the annexed claims.

What we claim as new and desire to secure by Letters Patent of the United States is:

1. Register control apparatus comprising the combination with an element operating on a strip of material, of light sensitive means controlled by the strip for producing an electrical impulse, light sensitive means for producing an electrical impulse in accordance with the position of said element, and means actuated by said impulses for varying the relationship between said strip and element in accordance with the order of occurrence of said impulses.

2. A register control system comprising in combination, an element operating on a strip of material, light sensitive means controlled by the strip for producing an electrical impulse, light sensitive means responsive to an indication produced on said strip by said element for producing a second electrical impulse and means actuated by said impulses for producing a correction in the relationship between said element and strip when the interval between said impulses exceeds a predetermined amount.

3. A register control system comprising the combination with an element operating on a strip of material, of a light sensitive device actuated by the strip, a second light sensitive device actuated in accordance with the position of said element, and means controlled by said light sensitive devices for introducing a correction in the relative positions of said strip and element selectively in a forward or reverse direction depending upon the order of actuation of said devices.

4. A control system comprising in combination, an element operating on a moving strip of material, a light sensitive device actuated by reference indicia on the strip, a second light sensitive device actuated by reference indicia produced on the strip in accordance with the operation of said element, means responsive to actuation of said devices for introducing a correction in the relative positions of said strip and element when the interval between the actuation of said devices exceeds a predetermined amount, and means for preventing operation of said corrective means

when said interval is less than said predetermined amount.

5. A control system comprising in combination, an element operating on a strip of material, a light sensitive device actuated by reference indicia on the strip, a second light sensitive device actuated by reference indicia placed on said strip in accordance with the operation of said element, means for introducing a correction in the position of the element relative to the strip if the time interval between said actuations exceeds a predetermined amount and in a direction depending upon the order of actuation of said devices, and means for maintaining said corrective means inactive when the interval between said actuations is less than said predetermined amount.

6. Register control apparatus comprising in combination, an element operating on a strip of material, means for correcting the relative positions of said material and element, an electric valve for controlling said means to produce a correction in one direction, a second electric valve for controlling said means to produce a correction in the opposite direction, a light sensitive device controlled by the strip for energizing said first valve, a light sensitive device actuated in accordance with said element for energizing said second valve, and means controlled by the first of said valves to be energized for preventing actuation of the other of said valves so that the direction of said correction depends upon the order of actuation of said light sensitive devices.

7. Register control apparatus comprising in combination, an element operating on a strip of material, a light sensitive device actuated by the strip, a second light sensitive device actuated in accordance with the operation of said element, electric valve apparatus responsive to actuation of said devices and means controlled thereby for producing a correction in the relative positions of said element and strip in a direction dependent upon the order of actuation of said devices, said valve apparatus serving to continue the correcting action after the actuation of said devices, and additional electric valve apparatus for rendering said first mentioned valve apparatus inactive a predetermined time after actuation of said light sensitive devices.

8. A control system comprising in combination, an element operating on a strip of material, an electric motor for correcting the position of the element relative to the strip; an electric valve for effecting operation of said motor in one direction, a second electric valve for effecting operation of said motor in the reverse direction, a light sensitive device actuated by the strip for actuating said first valve, a light sensitive device actuated in accordance with the position of said element for actuating said second valve, means responsive to the actuation of the first of said valves to be actuated for preventing actuation of the other of said valves when the interval between actuation of said light sensitive devices exceeds a predetermined amount so that the direction of the correcting action of said motor depends upon the order of actuation of said light sensitive devices.

9. A control system comprising the combination with an element operating on a moving strip of material, of an electric motor for correcting the position of said element relative to said strip, a pair of electric valves, a light sensitive device actuated by the strip for actuating one

of said valves, a light sensitive device actuated in accordance with the position of said element for actuating the other of said valves, means controlled by the first of said valves to be actuated for preventing action of the other of said valves after a predetermined interval of time, and means responsive to actuation of one of said valves for energizing said motor for rotation in a corresponding direction and responsive to actuation of both of said valves for preventing actuation of said motor.

10. A register controller comprising the combination with an element operating on a strip of material, of an electric motor for correcting the relative positions of said element and strip, a pair of electric valves containing an ionizable medium and supplied from a source of direct voltage whereby said valve remains active after an energizing impulse, a light sensitive device controlled by the strip for energizing one of said valves, a second light sensitive device actuated in accordance with the position of said element for energizing the other of said valves, means controlled by the first of said valves to be energized for preventing energization of the other of said valves after a predetermined time interval, means responsive to energization of either of said valves for energizing said motor for rotation in a corresponding direction, and 30 additional electric valve apparatus for deenergizing said electric valves after a predetermined time.

11. A register controller comprising in combination, an element operating on a strip of material, an electric motor for correcting the relative positions of said element and strip, a pair of electric valves each containing an ionizable medium and having an anode, cathode and control grid, and supplied from a source of direct voltage whereby it remains active after an energizing impulse, a light sensitive device controlled by the strip for energizing one of said valves, a second light sensitive device actuated in accordance with position of said element for energizing the other of said valves, means responsive to energization of one of said valves for applying a positive voltage to the cathode of the other of said valves to prevent energization of said other valve when the interval between actuation of said light sensitive devices exceeds a predetermined amount, and means responsive to energization of either of said valves for actuating said motor for rotation in a corresponding direction and responsive to energization of both said valves for maintaining said motor inactive.

12. A register control system comprising in combination, an element operating on a strip of material, an electric motor for correcting the relationship of the element and strip, electric valve apparatus supplied from a source of alternating voltage and having an output circuit connected to said motor and an input control circuit, electric valve apparatus supplied from a source of direct voltage and having an input control circuit and an output circuit connected to the input circuit of said alternating voltage valve apparatus, light sensitive means controlled by the relative positions of said element and strip for energizing said direct voltage valve apparatus whereby said alternating voltage valve apparatus is actuated to energize said motor, and additional electric valve apparatus actuated in response to energization of said direct voltage valve apparatus for deenergizing said direct

voltage valve apparatus after a predetermined interval of time.

13. A register controller comprising in combination, an element operating on a strip of material, a light sensitive device controlled by the strip for producing an electrical impulse in accordance with the position thereof, a second light sensitive device for producing an electrical impulse in accordance with the position of said element, means controlled by said impulses for correcting the relationship of said strip and element when the time interval between said impulses exceeds a predetermined amount for correcting the positional relationship of said strip and element, and means for adjusting the length of said interval.

14. A register controller comprising in combination, an element operating on a strip of material, a pair of electric valves, a light sensitive device controlled by the strip to produce an electrical impulse for actuating one of said valves, a second light sensitive device for producing an electrical impulse in accordance with the position of said element for actuating the other of said valves, means controlled by the actuation of one of said valves for preventing actuation of the other of said valves after a predetermined interval of time, variable condenser means in circuit with said valve apparatus for varying said time interval, and means responsive to actuation of either of said valves for producing a corresponding correction in the positional relationship of said element and strip.

15. A control system comprising in combination, an element for performing an operation on a length of material, light sensitive means controlled by said length of material for producing an electrical impulse, light sensitive means for producing an electrical impulse in accordance with the position of said element, and means actuated by said impulses and controlled in accordance with the order of occurrence of said impulses for indicating the positional relationship of said element and length of material.

16. A control system comprising in combination, an element for performing an operation on a length of material, light sensitive means controlled by said length of material for producing an electrical impulse, light sensitive means for producing an electrical impulse in accordance with the position of said element, and means actuated by said impulses for indicating the positional disagreement between said element and strip when the interval between said impulses exceeds a predetermined amount.

17. A control system comprising in combination, an element operating on a length of material, a light sensitive device actuated by reference indicia on the strip, a second light sensitive device actuated in accordance with the position of said element, means for indicating the positional relationship of said element and length of material if the time interval between said actuations exceeds a predetermined amount and for indicating the direction of positional disagreement of said element and length of material depending upon the order of actuation of said devices, and means for maintaining said indicating means inactive when the interval between said actuations is less than a predetermined time.

18. A control system comprising in combination, an element for performing an operation on a length of material, means for indicating the positional relationship of said element and length

of material, an electric valve for controlling said indicating means to produce an indication of positional disagreement of said element and length of material in one direction, a second 5 electric valve for controlling said indicating means to produce an indication of positional disagreement of said element and length of material in the opposite direction, a light sensitive device controlled by said length of material for 10 actuating said first valve, a second light sensitive device controlled in accordance with the position of said element for actuating said second valve, and means controlled by the first of said valves to be actuated for preventing actuation 15 of the other of said valves, so that the indication of the direction of disagreement depends upon the order of actuation of said light sensitive devices.

19. A control system comprising in combination 20 an element operating on a moving length

of material, means for indicating the positional relationship between said element and length of material, a pair of electric valves, a light sensitive device actuated by the length of material for actuating one of said valves, a light sensitive device actuated in accordance with the position of said element for actuating the other of said valves, means controlled by the first of said valves to be actuated for preventing actuation of the other of said valves after a predetermined 10 interval of time and means responsive to actuation of one of said valves for controlling said indicating means to produce an indication of positional disagreement of said element and length of material in a corresponding direction 15 and responsive to actuation of both of said valves for preventing actuation of said indicating means.
